UNITED STATES PATENT OFFICE.

PETER BISSEN, OF STACYVILLE, IOWA.

LOADING APPARATUS.

No. 890,553.

Specification of Letters Patent.

Patented June 9, 1908.

Original application filed February 23, 1907, Serial No. 358,887. Divided and this application filed October 18, 1907. Serial No. 398,051.

To all whom it may concern:

Be it known that I, PETER BISSEN, a citizen of the United States, residing at Stacyville, in the county of Mitchell and State of Iowa, have invented certain new and useful Improvements in Loading Apparatus, of which the following is a specification.

This application is a division of my pending application No. 358,887, filed Feb. 23, 1907.

The invention is a loading apparatus, and has for its object to provide a portable apparatus which can be moved about for different kinds of work, and which includes a derrick or hoisting frame of novel construction, as well as a bucket or hopper provided with doors at the bottom so that it can be dumped, and including improved means for closing said doors.

The invention is illustrated in the accompanying drawings in which

Figure 1 is a side elevation of the apparatus. Fig. 2 is an end elevation thereof. Fig. 3 is a top plan view.

Referring specifically to the drawing, the derrick which supports the hoisting apparatus is mounted on spaced parallel sills 10 and 11, respectively, provided with shoes or runners 12 so that the apparatus may be hauled about. To both ends of the sills are secured clevises 13 for attachment of draft devices. The posts or uprights of the derrick indicated at 14, 15, 16 and 17, respectively, are secured in pairs to the sills by angle-irons 18, the posts 14 and 15 being secured to the sill 10 and the posts 16 and 17 to the sill 11. The members of each pair of posts are suitably spaced apart and connected by cross-braces 19, and at the top said members are joined by a cross-rod 20 which passes through the posts and is secured by cotters 21. The posts of one sill are also connected at the top to the opposite posts of the other sill in such a manner that the derrick can be set closer together to enable it to pass through a gate or along a narrow road or passage when transporting it. This connection comprises cross-bars 22 which are spaced apart by blocks and bolted together. The cross-bars are ar-

50 ranged between the posts 14 and 16, and have laterally offset ends 23, which extend on opposite sides of said posts and are connected

to the rods 20 by passing the latter through holes in the said ends. The posts 15 and 17 are connected in a similar manner by cross-bars 24. The cross-bars 23 and 24 are connected by diagonal braces 25. The hoisting tackle to be hereinafter described is suspended from clips 26 which are secured to the cross-bars 22 and 24. The derrick also has braces 27 and 28, respectively, which are fastened at one end to collars 29 on the posts, and at the other end to the clips 26. The braces 28 are chains or other flexible devices so that the posts can be set closer together as heretofore described.

The double box 30 which receives the material to be loaded is more particularly described and claimed in my pending application. It is hoisted by means of a drum 43 on which the hoisting tackles 44 are wound. The box is divided into two compartments and a tackle is provided for each end of the box. At the bottom of the box are doors 32 and 33 which are hinged to the sides of the box and meet at the middle, and open by swinging downwardly and outwardly. They are held closed by a latch 35, fully described in my pending application.

To provide novel devices for closing the doors I use a rope 40 which extends over a pulley 41 supported by a cross-bar 42 which is secured at its ends to the bars 22 and 24 heretofore described and which is bolted at the middle to the braces 25. The rope 40 is connected by a ring to a pair of links 44 which have loops 45 at their lower ends adapted to engage hooks 46 secured to the edges of the doors 32 and 33. The loops 45 can be quickly engaged or disengaged, and the length of the links is sufficient to allow the doors to swing almost to a vertical position.

The apparatus is designed especially for loading manure spreaders, although it can be used for various other purposes. To load spreader, the box is lowered to the ground and the material is thrown therein. When the box is full it is hoisted and the spreader is driven thereunder. The latches 35 are then released, allowing the doors 32 and 33 to swing open, and the material is dumped.

When not in use the apparatus can be moved under cover the derrick construction

herein described enabling it to be narrowed sufficiently to be passed through a gate or along narrow places, and inasmuch as the derrick is portable, it can be readily moved 5 about and used for various purposes.

After the material in the box is dumped the rope 40 is loosened at its cleat 47, and the links 44 are connected to the hooks 46. The rope 40 is then drawn taut and fastened at 10 the cleat, and the box is lowered, and as it descends, the links draw the doors together until they are closed, at which instant they are fastened by the catch or latch 35. The rope 40 is then slackened and the loops 45 drop 15 away from the hooks 46, and the links can then be drawn up to suspended position for next operation. This manner of closing the doors saves labor, and is advantageous in

handling dirty material, since the operators do not have to lift the doors by hand.

20

I claim:

A derrick comprising spaced ground sills, posts mounted in pairs on the sills, a pivot rod connecting the posts on each sill at the top thereof, a pair of cross bars at each end 25 at the top between the posts of one sill and those of the other, the bars of each pair being spaced apart at the ends and connected to the said rods on each side of each post.

25

In testimony whereof I affix my signature, 30 in presence of two witnesses.

PETER BISSEN.
